FUSE

Carl E. O. Kriegstedt, Washington, D. C., assignor to The Engineering Appliance Corporation, a corporation of Delaware

Application January 15, 1932. Serial No. 586,719

1 Claim. (Cl. 200—121)

The present invention relates to electric fuses and more particularly to fuses of the cartridge type having amongst its principal objects to provide an attachment for such, as will permit of the more ready handling of the fuses, especially when inserting or withdrawing the same from its connection within an electrical circuit, in which it is to be used.

One very important object of this invention is to provide a novel signalling device in connection with such a fuse, the device being in the form of a miniature lamp which is caused to glow whenever the fuse element is fused or "blown" by excess current, and it is to be noted that this lamp thus immediately indicates to a repair man which fuse of a number of fuses is to be replaced.

A further object of the present invention is to provide a combined pilot light housing and handle for fuses of the cartridge type, which will not only permit of the safe handling of the fuse when connecting the same within an electric circuit, but which has within the housing a signalling member capable of visibly indicating when the fusible element of the fuse has been ruptured.

With the above and other objects in view as will be hereinafter apparent, the invention consists in general of certain novel details of construction and combinations of parts hereinafter fully described, illustrated in the accompanying drawing and specifically claimed.

In the accompanying drawing like characters of reference indicate like parts in the several views, and:

Figure 1 is a side elevation of the improved fuse.

Figure 2 is an end view thereof.

Figure 3 is a longitudinal sectional view of the same.

Figure 4 is an end view of the fuse with the covering cap adjacent the observer removed.

In the embodiment of the invention as herein disclosed there is provided a body including a central tubular portion 10 which is made of some suitable insulating material. Each end of this portion 10 is externally threaded and on each of these threaded ends is screwed a metallic nipple or inner cap 11 having its outer end reduced and closed by a diaphragm 12 except that each diaphragm is provided with a pair of parallel slots 13. Furthermore, the tube 10 is provided with a lateral vent opening 14. The outer end of each inner cap 11 is externally threaded and on each threaded end is screwed a covering or outer cap 15 which has a knurled periphery so that un-

der normal conditions it may be screwed on or off its inner cap by gripping with the fingers. However, a screw kerf 16 is provided for the outer cap so that a screw driver may be used in case the covering cap sticks and cannot be worked by the fingers. A fusible strip 18 of the usual soft alloy metal is positioned in the tube 10 with each end extending through a slot 13 of a respective inner cap 11 and is bent at its ends so that these ends are clamped between the covering caps 15 and 65 the inner caps 11 as shown best in Figure 3.

By means of this arrangement the strip 18 may be readily renewed at any time since all that is necessary is to unscrew the caps 15 and, after removing the old strip, thread a piece of fuse 70 strip through respective slots. One end is then bent over and held by replacing the covering cap at that end. The strip may then be pulled tight, bent over and cut off. Finally the remaining covering cap is screwed on. Thus the 75 active or useful length of the replacement will be equal to that of the strip which is replaced and the fuse will accordingly always have the same capacity so long as the fuse strip is of the same cross-sectional area. Moreover, the ca- 80 pacity of this fuse may be varied at will by using fuse stripping of desired cross-section. The foregoing description taken in connection with the drawing, discloses a cartridge type of fuse which is now in general use, but the invention 85 has reference to a pilot light or indicator for this type of fuse, which will now be described.

The lamp body or housing consists of a central tubular portion 19 having a metallic cap 20 on each end and these caps are brazed or otherwise 90 conductively fixed to the respective inner caps 11. By so permanently fixing the lamp housing 19 to the fuse casing 10, the former will project beyond the clips of the fuse block (not shown) when the fuse is connected to the latter, thereby 95 not only providing a lamp housing but a projecting handle by which an operator may easily and readily take hold of the fuse for withdrawing the same from the clips of the fuse block. A sight window 21 is provided in the tube 19 on the side 100 remote from the tube 10. In the tube 19 opposite the window 21 is a miniature lamp 22 which has one terminal connected by a conductor 23 to one of the caps 20 while the other terminal of the lamp is connected by a conductor 24, 105 having a resistance element 25 interposed in its length, to the remaining cap 20. The miniature lamp or other luminous indicating means indicated by the numeral 22 upon the drawing, is 110 preferably a small sealed glass tube charged with

gas under pressure and provided with suitable electrodes, the gas being of a character that produces a luminous glow when an electric current is passed therethrough, the pressure of the 5 gas and the spacing of the electrodes being determined by the voltage to be impressed on the electrodes, and having a current limiting resistance in series with one of the electrodes. The tube herein shown is preferably designed so 10 that it will glow with a current of four microamperes, said amount being amply provided by an alternating current circuit having a capacity of .301 mf. The resistance 25 is sufficient to cause substantially all of the current of the circuit in which the fuse is used to flow through the strip 18 so long as the latter is intact. However, if the strip 18 is fused then sufficient current will 15 flow through the resistance and lamp to cause the latter to glow, thus giving a visible indication of the blowing of the fuse.

Should a short circuit occur in the electrical circuit in which this fuse is included, the fuse element 18 will first blow or be ruptured whereupon the current will be directed through the 20 resistance 25 and the lamp 22 and the latter giving off a glow indicating that the fuse element has been blown. This lamp will continue to glow even after the cause of the short circuit is removed and the electrical circuit again opened 25 due to the fact that the lamp 22 has such a small current consumption. The resistor 25 not only protects the lamp 22 from excessive current flowing therethrough but obviously will protect any delicate instruments that may be included 30 in the electrical circuit. The lamp 22 draws its energy through a capacity effect, and accordingly, will continue to flow even after the cause of the 35 short circuit is removed and the circuit is open.

As the lamp body or housing 19 is permanently attached and separated from the housing or casing 10 of the fuse, it may be utilized in the handle for causing the cartridge fuse to be inserted within or withdrawn from the terminal clip of 80 the electric circuit in which it is to be used, thereby preventing the operator from coming in contact with the terminals of the electric circuit and protecting him against injury.

There has thus been provided a simple and efficient device of the kind described and for the 85 purpose specified.

It is obvious that minor changes may be made in the form and construction of the invention without departing from the material spirit thereof. It is not, therefore, desired to confine 90 the invention to the exact form herein shown and described, but it is desired to include all such as properly come within the scope claimed.

Having thus described the invention, what is 95 claimed as new, is:

A fuse unit comprising a casing, contact terminals arranged at the outer ends of said casing, a fusible element housed within said casing and electrically connected to said contact terminals, 100 a side extension permanently secured to said casing, said side extension being retained in spaced relation to said casing and constituting a handheld, said side extension being formed with a sight opening, a glow lamp positioned 105 within said side extension, a resistor located within said side extension, and independent means in parallel with said fusible element for connecting said glow lamp and resistor in series 110 with said terminals whereby the rupture of the fusible element may be visibly indicated through the sight opening of said side extension.
